UNITED STATES PATENT OFFICE.

WILLIAM H. SHELLINGTON, OF TICONDEROGA, NEW YORK, ASSIGNOR TO INTERNATIONAL PAPER COMPANY, A CORPORATION OF NEW YORK.

PAPER-CUTTING DEVICE FOR PAPER-MAKING MACHINES.

1,402,451.

Specification of Letters Patent. Patented Jan. 3, 1922.

Application filed September 27, 1918, Serial No. 255,936. Renewed November 23, 1921. Serial No. 517,381.

To all whom it may concern:

Be it known that I, WILLIAM H. SHELLINGTON, a citizen of the United States, residing at Ticonderoga, in the county of 5 Essex and State of New York, have invented certain new and useful Improvements in Paper-Cutting Devices for Paper-Making Machines, of which the following is a specification, reference being had therein to the 10 accompanying drawing.

This invention relates to paper making machines, and has reference more particularly to mechanical means for severing or cutting the paper sheet or web to facilitate 15 its introduction or stacking in the calender rolls.

In the operation of paper making machines, the paper sheet from the forming wire passes alternately around upper and 20 lower drying cylinders by which the damp sheet is dried, thence to calender rolls which give the sheet its calendered finish, and is finally wound in a roll on a winding roll. It not unfrequently happens that in the passage 25 of the sheet through the machine, it breaks or parts before it reaches the calender rolls, and consequently it is necessary, after the travel of the new sheet has been re-established, to enter the front end 30 of the same into the calender rolls. This re-entry of the sheet in the calender rolls, or "stacking" as it is termed in the trade, has been the cause of annoyance, delay and wastage of paper, the practice so far as I 35 am aware, being for the attendant to tear the new sheet across on a diagonal line where it passes from the last drying cylinder, in order to leave a tongue or projecting portion at one edge to be entered in the calender rolls. The operation thus performed 40 is slow and uncertain and results in an accumulation and loss of the paper as it continues to pass from the drying cylinders, while the attendant is inserting the end in 45 the calender rolls. The operation also requires the attention and aid of two or more attendants who usually work at this part of the machine. A further objection is that, due to the uncertain and uneven tearing action 50 as performed by hand, there is liability of the paper failing to enter the calender rolls smoothly and uniformly; and it may become bunched and clog the calender rolls and cause breakage or serious injury.

55 My invention aims to overcome these ob-

jections, and it consists in the provision of a mechanical cutting device which may be operated by a single attendant to cut or incise the sheet, preferably where it passes from one drying cylinder to the next at the 60 end of the series, the cutting action being speedily performed in a uniform manner, and such that a tongue or projection will be left on the end of the sheet to facilitate its entry into the calender rolls. As a result, the end of the new sheet may be entered by the attendant into the calender rolls in a uniform and smooth manner and without the liability of the formation of bunches or the clogging of the rolls, and 70 with a minimum of waste.

The invention consists also in so constructing and mounting the cutting device that its actuation to incise the sheet will be effected by power means under the control of 75 the attendant.

In the accompanying drawings:

Fig. 1 is a side elevation of the dry end of a paper making machine having my invention embodied therein.

Fig. 2 is a similar view on an enlarged scale, of the terminal portion of the series of drying cylinders with my cutting device applied.

Fig. 3 is an elevation on an enlarged scale 85 of the cutting device and one form of operating means, said parts being detached from the machine.

Fig. 4 is a similar view showing a form of power means for operating the cutting devices.

Fig. 5 is a vertical cross section on the line a—a of Fig. 4.

Fig. 6 is an end elevation of the device shown in Fig. 4 looking in the direction of 95 the arrow in said figure.

Fig. 7 is a view in the nature of a diagram showing how the paper sheet is cut by the device.

Referring to the drawings:

Referring particularly to Fig. 1, 1 designates the terminal portion of the series of drying cylinders arranged as usual in the sustaining frame 1^a in upper and lower rows, with the cylinders 1^b of the upper row alternating with the cylinders 1^c of the lower row; and 2 designates the paper sheet or web from the forming wire, (not shown), which sheet passes continuously in the rotation of the drying cylinders alternately around the 110

upper sides of the upper cylinders and the lower sides of the lower cylinders, so that it will be subjected on opposite sides to a drying action. 3 designates the calender rolls sustained as usual one above the other in a suitable sustaining frame 3^a, around which rolls the dried sheet passes from the last drying cylinder, and by which the sheet is given a finished or calendered surface; and 4 designates a winding roll rotatably mounted in a frame 4^a, and onto which the paper sheet is wound after it leaves the calender rolls.

The foregoing parts may be of the usual and ordinary construction well known to those skilled in this art, and in themselves they form no part of the present invention.

5 designates the cutting device constituting the present invention, which device is preferably in the form of a pointed cutter or needle 5^a, and which cutting device is sustained preferably by the frame of the drying cylinders so that it will act on the paper sheet where it passes from the last lower drying cylinder 1^b to the last upper drying cylinder 1^c, the said needle being so sustained and mounted that it may be swung by the attendant inwardly from a normal inoperative position out of contact with the paper sheet, to an operative position in contact with the same, and may then be moved transversely of the direction of travel of the sheet to incise the same cross-wise.

To effect these actions, the needle is fixed at its inner end to a slide or block 6 so as to extend radially therefrom, which slide is mounted to move back and forth in a casing or guide tube 7, with the needle projecting through a longitudinal guide slot 8 in the tube. The guide tube extends from front to rear, parallel with the axes of the drying cylinders and is mounted at its ends to rock in bearings 9 and 10 sustained respectively by front and rear brackets 11 and 12 fixed to the frame 1^a at its front and rear and projecting inwardly toward the paper sheet. The front bearing 9 is formed in its upper side with a slot 13 through which projects a handle 14 having its inner end fixed to the guide tube, so that the latter may be rocked by the handle back and forth, which action, due to the engagement of the walls of the slot 8 with the needle, will correspondingly rock the latter. The length of the slot 13 and the relation of the parts is such that when the handle is swung to the left as shown in Fig. 1 the needle will be sustained in an outward inoperative position with its cutting end free of the paper sheet as shown by dotted lines in Fig. 2, and when the handle is moved inwardly, the needle will be moved to an operative position extending inwardly toward the paper with its cutting end in engagement with the same. The slide has attached to its front end as shown in Fig. 3, an operating member 15 in the form of a piece

of flexible hose which extends outwardly beyond the end of the tube within reach of the attendant, and by means of which the slide and needle carried thereby may be moved longitudinally along the tube to cause 70 the cutting end of the needle to traverse the paper sheet and cut or incise the same.

The operation of the mechanism so far described is as follows: Assume that the sheet has parted or broken and the new sheet 75 has been started by the attendants and is feeding through the drying cylinders and passing downwardly from the last cylinder as shown by dotted lines in Fig. 1; and assume also that the cutting needle is in an 80 outward inoperative position as shown in said figure with its cutting end free of the paper sheet passing upwardly from the last lower drying cylinder to the last upper cylinder. The attendant while the sheet is traveling, grasps the handle 14 and swings the same inwardly, thereby correspondingly swinging the cutting needle and engaging its cutting end with the traveling sheet, care being taken that the slide 6 will be at the 85 forward part of the guide tube in such position that the needle will engage the sheet some distance, say 12 to 18 inches, from its front edge. As the sheet continues to feed with the needle in engagement therewith, 90 the latter will form in the sheet a straight incision A, Fig. 7, thereby separating from the main sheet a marginal strip A' at the front edge to be subsequently entered by hand in the calender rolls. When the marginal strip thus formed leaves the last drying cylinder the attendant separates the front end of the strip from the main sheet by tearing through the connecting portions of the two, and as the sheet continues to 100 come from the drying cylinders and the needle continues to incise the same, the separated tongue will increase in length, and the attendant takes hold of the free end of the tongue and carries it up to the top calender rolls and enters the same therebetween. The rotation of the calender rolls begins to feed the tongue therethrough, while the main portion of the sheet runs down from the last drying cylinder, and when the tongue is feeding properly through the calender rolls, and the sheet is pulling tight between the two last drying cylinders, the attendant by means of the operating hose 15, moves the slide and attached cutting needle longitudinally along the guide tube rearwardly through the remaining width of the sheet. This action will form an incision B in the sheet extending cross-wise thereof, which, due to the continued travel of the sheet, will be on an inclination. After the sheet has been thus finally severed, the attendant grasps the handle 14 and swings the needle outwardly to an inoperative position, and then by means of the hose 130

15, the slide and attached needle are drawn to the front again for the next operation.

I propose to provide power means for moving the cutting needle along the guide tube, and controlling means for throwing the power means into action, so that after the needle has been swung into operative position in engagement with the sheet, the stacker or attendant working at the calender 5 rolls, may throw the power mechanism into action and cause the needle to traverse the sheet and effect the cross-wise cut, without the aid of other attendants. In the present instance this action is effected by the mechanism shown in Fig. 4, where it will be seen that a cord or cable 16 has its opposite ends connected respectively with the opposite ends of the slide 6 within the guide tube as at 16^a and 16^b, and passes between its 10 ends outside the tube and around vertical guide pulleys 17, 17 rotatably sustained by the brackets 11 and 12 outwardly of the ends of the tube and below the same. A weight 18, Figs. 1 and 4, is attached to one end of a cord or cable 19 which passes upwardly 15 over a guide pulley 20 and then downwardly around a second guide pulley 21 sustained by the frame 1^a at the back. The opposite end of the cord is attached to the rear end of 20 the needle carrying slide within the guide tube as at 21^a, the tendency of the weight being to draw the slide toward the rear. The weight is supported in elevated position, 25 with the slide at the forward part of the guide tube, by means of a trigger or detent 22 pivoted between its ends on a bracket 23 attached to the frame 1^a, the lower end of the trigger being provided with a finger 22^a adapted to enter an eye 24 on the upper end 30 of the weight, and the upper end of the trigger being provided with a horizontal arm 25 for the attachment of a controlling or tripping cord 26. This cord passes upwardly over a guide pulley 27 sustained by 35 the frame 1^a and then laterally to the frame of the calender rolls, where it passes over guide pulleys sustained by said frame and extends to the front of the frame within reach of the attendant or stacker. In the 40 operation of severing the sheet after the handle 14 has been swung inwardly to engage the needle with the same, the attendant by pulling on the cord 26 rocks the trigger on its axis, which action will draw 45 the finger 22^a from the eye on the weight and release the latter, and the weight moving down by gravity, will draw the slide and attached cutting needle to the rear and thereby incise the sheet cross-wise. Due to this 50 construction, the cutting device is under the complete control of the stacker or attendant working at the calender rolls, and enables him without the aid of other attendants, to 55 form the tongue on the new sheet, enter the 60 same in the calender rolls, and effect the 65

cross-wise cut of the sheet. The operation may be performed speedily and with uniformity, and ensures that the new sheet will enter the calender rolls smoothly and evenly and without liability of bunching 70 or clogging the rolls. Furthermore by the operation of the device, the accumulation of the paper to an objectionable extent between the drying cylinders and the calender rolls is avoided, and the wastage of paper 75 consequently reduced to a minimum.

In the foregoing description and accompanying drawings I have set forth my invention in the particular detailed form which I prefer to adopt, but it will be understood that these details may be variously changed and modified without departing from the spirit of the invention; and further it will be understood that the invention is not to be limited to any particular form or 80 construction of the parts except in so far as such limitations are specified in the claims.

Obviously it is not essential to the invention that the cutting needle be arranged as shown in full lines and as above described, 85 to act on the sheet where it passes from the last lower drying cylinder to the last upper drying cylinder as good results can be secured if it is applied to act at other points, for instance as shown by dotted lines to the 90 right in Fig. 2.

Having thus described my invention, what I claim is:

1. In a paper making machine, the combination of a series of paper drying cylinders 100 through which series the paper sheet travels, and a paper cutting member provided with a cutting portion, said member being sustained in position to act on the paper sheet in its travel through the series of drying cylinders and being operable to cause its cutting portion to engage and incise the sheet 105 in said travel, to facilitate the entry of the sheet between the calender rolls.

2. In a paper making machine, the combination of a series of paper drying cylinders through which series the paper sheet travels, and a paper cutting member provided with a cutting portion, said member being sustained in position to act on the sheet in its 110 travel through the series of drying cylinders, and said cutting member being operable to cause its cutting portion to engage and incise the sheet in a direction crosswise of its travel, to facilitate the entry of the sheet 115 between the calender rolls.

3. In a paper making machine, the combination of a series of paper drying cylinders through which series the paper sheet travels, and a paper cutting member provided with a 120 cutting portion, said member being sustained in position to act on the sheet in its travel through the series of drying cylinders, and said cutting member being operable to cause 125 its cutting portion to engage and incise the sheet in a direction crosswise of its travel, to facilitate the entry of the sheet 130 between the calender rolls.

sheet both in the direction of its travel and crosswise of its travel, to facilitate the entry of the sheet between the calender rolls.

4. In a paper making machine, the combination of a series of paper drying cylinders through which series the paper sheet travels, and a paper cutting member provided with a cutting portion, said member being sustained in position to act on the sheet in its travel 10 through the series of drying cylinders and being operable to cause its cutting portion to engage and incise the sheet substantially throughout its width to facilitate the entry of the sheet between the calender rolls.

15. 5. In a paper making machine, the combination of drying cylinders for the traveling paper sheet, and a paper cutting member provided with a cutting portion, said member being sustained in position to act on the 20 traveling sheet and being operable to cause its cutting portion to engage and incise the sheet at or adjacent the point where it passes from one drying cylinder to the next.

6. In a paper making machine, the combination of drying cylinders for the traveling paper sheet, and a paper cutting member provided with a cutting portion, said member being sustained in position to act on the traveling sheet, and being operable to incise 30 the sheet in a direction crosswise of its travel at or adjacent the point where it passes from one drying cylinder to the next.

7. In a paper making machine, the combination of drying cylinders for the traveling paper sheet, and a paper cutting member provided with a cutting portion, said member being sustained in position to act on the traveling sheet and being operable to incise 40 the sheet at or adjacent the point where it passes from one drying cylinder to the next, both in the direction of its travel and crosswise thereof.

8. In a paper making machine, the combination of a series of drying cylinders through which series the paper sheet travels, and a paper cutting member provided with a cutting portion, said member being sustained in position to act on the sheet in its travel through the drying cylinders; and 50 being movable from an inoperative position free of the sheet toward the same to cause its cutting portion to engage the sheet, and being movable also transversely of the travel of the sheet to cause its cutting portion to incise the same crosswise.

55. 9. In combination with a paper making machine provided with paper drying cylinders, a paper cutting device applied to the machine at or adjacent the drying cylinders 60 and movable to incise the dried paper sheet, and power operated means acting on said device to move the same.

65. 10. In combination with a paper making machine provided with paper drying cylinders, a paper cutting device applied to the

machine at or adjacent the drying cylinders and movable to incise the dried paper sheet, power operated means adapted to act on the cutting device to move the same, and controlling means for throwing the power means into action. 70

11. In combination with a paper making machine, a paper cutting device applied thereto and movable transversely of the direction of travel of the paper sheet to incise 75 the same cross-wise, a weight operatively connected with the cutting device to move it, and a releasable member for sustaining the weight elevated.

12. In combination with a paper making machine, a paper cutting device applied thereto and movable transversely of the direction of travel of the paper sheet to incise 80 the same cross-wise, a weight operatively connected with the cutting device to move it, 85 a releasable member for sustaining the weight elevated, and means attached to said member for releasing it.

13. In a paper making machine, and in combination with a frame, a guide member 90 sustained thereby and extending transversely of the direction of travel of the paper sheet, and a cutting device projecting laterally from the guide member and movable longitudinally thereof to act on the paper sheet, means attached to the cutting device for moving it longitudinally, said guide member being rockable on its longitudinal axis to move the cutting device into and out of engagement with the sheet 95 and being provided with a projecting portion independent of said means, for rocking it. 100

14. In a paper making machine, and in combination with the frame, a guide member 105 sustained thereby and extending transversely of the direction of travel of the paper sheet, a cutting device projecting laterally from the guide member and movable longitudinally thereof to act on the paper sheet, said guide member being rockable on its longitudinal axis to move the cutting device into and out of engagement with the sheet, a handle attached to the guiding member for rocking it, and means connected 110 with the cutting device and independent of the handle for moving it longitudinally of the guide member. 115

15. In a paper making machine and in combination with the frame, a guide member 120 sustained thereby and extending transversely of the travel of the paper sheet, a cutting device sustained by the guide member and movable longitudinally thereof, a 125 cord attached at its opposite ends to the cutting device and passing between its ends around guide pulleys, and an actuating cable connected with the cutting device for moving it longitudinally of the guide member. 130

16. In a paper making machine, and in combination with the frame, a guide tube sustained by the frame to rock on its longitudinal axis and extending transversely of the travel of the paper sheet, said tube being provided with a longitudinal slot, a slide movable longitudinally within the tube, a cutting device fixed to the slide and projecting outwardly through the slot in the tube to act on the paper sheet, means attached to the slide for moving it longitudinally and a handle fixed to the tube for rocking it to move the cutter into and out of engagement with the paper sheet.
17. In a paper making machine and in combination with the frame, a guide tube sustained thereby and extending transversely of the travel of the paper sheet and provided with a longitudinal slot, a slide movable longitudinally in the tube, a cutting device connected with the slide and projecting outwardly through the slot in the tube, a cord connected at its opposite ends to the opposite ends of the slide within the tube, and extending between its ends outside the tube, a second cord attached at one end to the slide, and a weight attached to the cord for moving the slide in the tube.
18. In a paper making machine, and in combination with a series of drying cylinders through which series the paper sheet travels toward the calender rolls, a paper cutting device movable transversely of the direction of travel of the sheet and in engagement with the same to incise the sheet crosswise, power means acting on the cutting device to move the same, and controlling means for the power means extending within reach of the attendant working at the calender rolls.
19. In a paper making machine, and in combination with a series of drying cylinders through which the paper sheet travels, a paper cutting member provided with a cutting portion, and sustained in position to act on the paper in its travel through the series of drying cylinders, said member being operable to form an incision near one edge of the sheet in the direction of its travel, and being operable also to form a connecting incision crosswise of the remaining portion of the sheet, to facilitate the entry of the sheet between the calender rolls.
20. In a paper making machine through which the paper sheet travels in its advance to the calender rolls, the combination of a member provided with a paper cutting portion, said member being sustained in position to act on the dried sheet and being operable to cause its cutting portion to engage the traveling sheet and sever the same through substantially its width whereby the severed end of the sheet may be entered directly between the calender rolls to re-establish its feed.
21. The method of manipulating the traveling paper sheet in a paper making machine to reestablish its feed through the calender rolls, which consists in forming an incision in the traveling sheet at or adjacent the drying cylinders in the direction of its travel to leave a strip, serving the strip from the body portion of the sheet to free one end of the strip and thereby form a tongue, entering the tongue directly between the calender rolls, and serving the sheet through its remaining body portion.
22. The method of manipulating the traveling paper sheet in a paper making machine to reestablish its feed through the calender rolls, which consists in forming an incision in the traveling sheet at or adjacent the drying cylinders in the direction of its travel to leave a marginal strip, severing the strip from the body portion of the sheet to form a tongue, directly entering the tongue between the calender rolls and finally continuing said incision but in a crosswise direction through the remaining body portion of the sheet to completely sever the same.

In testimony whereof, I have affixed my signature hereto.

WILLIAM H. SHELLINGTON.
